[57] **CLAIM**

The ornamental design for a ball rolling game stick, as shown and described.

DESCRIPTION

FIG. 1 is an isometric view of a ball rolling game stick, showing our new design;

FIG. 2 is a top plan view;

FIG. 3 is a bottom plan view;

FIG. 4 is a front elevational view;

FIG. 5 is a rear elevational view;

FIG. 6 is an elevational view of one side, the opposite side being a mirror image.
